STORAGE CABINET FOR ICE CREAM AND
THE LIKEWilliam P. Crisman, Takoma Park, Md., assignor
to Southern Dairies, Inc., Washington, D. C.,
a corporation of Delaware

Application August 16, 1937, Serial No. 159,384

13 Claims. (Cl. 62—89)

This invention relates to cold storage cabinets and more particularly to those types of cabinets which are used for ice cream service in retail stores.

5 In my copending application Serial No. 131,077 I have described and claimed a cabinet of the two-high receptacle type in which is incorporated means for supporting the receptacles of the upper tier and facilitating access to the receptacles of 10 the lower tier. As explained in that application, ice cream and the like is kept in bulk in such cabinets, under refrigeration, and the cream is dipped from cans or other receptacles as customers call for it. Until comparatively recently, 15 it was customary to stock the cabinets with ice cream in five-gallon cans, but the best present practice substitutes two-and-one-half gallon cans to provide a wider range of available flavors and kinds of ice cream and analogous goods and 20 to permit emptying and replenishment of the cans at shorter intervals so that the stock on hand is always comparatively new and fresh.

The two-and-one-half-gallon cans are commonly of the same diameter and of approximately one-half the height of the five-gallon cans. Used in the same cabinets, the shorter cans are stacked two high, and inasmuch as the cabinets invariably have closed sides and bottoms and are provided with top openings only, it has 25 been necessary to provide means for rendering the cans in the lower zone of the cabinet conveniently accessible to an attendant reaching through the top opening. Unless some such special means be provided it would be necessary, 30 in the case of a well filled cabinet, bodily to remove from the cabinet an upper can to reach a lower one, and this is manifestly inconvenient, unsanitary, time-consuming, and wasteful of refrigeration.

40 In my copending application above identified I disclosed a cabinet provided with means for rendering the lower cans or goods readily accessible through the top opening. The present invention provides a different type of means for 45 this purpose, having certain advantages over my earlier construction and over the best of the prior art devices with which I am acquainted, among which advantages the following may be mentioned:

50 The new construction excels in simplicity, low cost and ease of installation. For use in cabinets of multiple width, containing cans in two or more longitudinally extending rows set aside by side, the new construction is superior to any other cabinet of which I am aware. Its internal

structure, including each pair of superposed cans, occupies a minimum of vertical space with the parts at rest and requires no additional vertical space when the parts are moved to gain access to a lower can, so that the new construction can 5 be installed in cabinets having insufficient internal depth to accommodate the prior devices. This is a feature of particular importance in the case of certain rebuilt cabinets, as will be explained hereinafter. The present invention also 10 includes a further feature which I believe to be broadly new in refrigerating cabinets generally, i. e., a horizontal partition substantially completely separating the upper and lower zones of the cabinet when the parts are in normal position so that heat transfer by convection from one 15 zone to the other is substantially prevented. This arrangement minimizes the inter-zone temperature differential, reduces refrigerating losses, and by permitting the maintenance of more equable 20 temperatures and more accurate control thereof lessens the depreciating effects of storage on the products in the cans.

Additional objects are concerned with generally improving the accessibility of the cabinet 25 contents, particularly the cans in the lower zone thereof, preventing adhesion of the cans to the can supporting elements and ancillary structure, preventing undesired movement of the cans, particularly while dipping thrusts are being made into 30 their contents, maintaining the cans in accurate alignment with the top openings of the cabinet, and in effecting other and further advantages which will sufficiently appear from the description hereinafter of the invention in certain pre- 35 ferred forms of embodiment.

For the purpose of illustrating the invention, I have shown in the accompanying drawings, and will now proceed to describe, certain embodiments of the invention which are at present preferred by me since the same have been found in practice to give satisfactory and reliable results in accomplishing all the objects set forth hereinabove, as well as others.

In the drawings,

Figure 1 is a top plan view, partly broken away to show the interior of a cabinet provided with an embodiment of the invention;

Fig. 2 is a vertical longitudinal section;

Fig. 3 is a perspective view of one form of receptacle-supporting tray;

Fig. 4 is a cross sectional view taken on the line 4—4 of Fig. 3;

Fig. 5 is a detail view of a receptacle-supporting tray with one portion in raised position;

45

50

55

Fig. 6 is a cross sectional view of a modified form of receptacle-supporting tray; and

Fig. 7 is a cross sectional view of a further modified form of receptacle-supporting tray.

Referring to the drawings, the reference numeral 1 designates generally a cold storage cabinet of familiar form and widespread use in retail outlets for ice cream and the like. The cabinet construction is old per se and consists of an insulated box having closed sides, ends and bottom, top openings 2 closed by lids 3, and a coil or other refrigerating means 4 positioned in heat exchange relation with the cabinet interior, as by being built into the cabinet walls. The illustrated cabinet 5 net is of approximately forty gallons capacity, being capable of accommodating eight five-gallon cans or sixteen two-and-one-half-gallon cans or the equivalent thereof. The cans are arranged in two horizontally adjacent longitudinally extending rows, and eight top openings are provided, each aligned with one of the five-gallon cans or the equivalent space. As I have explained, in the preferred present day use of these cabinets half size cans stacked two high are substituted for the full size cans formerly used. According to the present invention as many as twelve two-and-one-half-gallon cans may be used in lieu of the eight five-gallon cans. In the drawings the lower cans are designated 5, and the upper cans 30 are designated 6. In the illustrated example, twelve rather than sixteen half size cans or their equivalents are used because the cans of the upper tier of each row are intended to be moved to provide access to the cans or space in the lower tier, and to accommodate such movement a blank or unoccupied space equal to the volume of one can must be provided in the upper tier for each pair of cans in the lower tier. These unoccupied spaces are designated 7 in the drawings.

To support the cans 6 of the upper tier I provide a series of trays 8, one for each can of the upper tier, each tray overlying a pair of adjacent cans 5 of the lower tier. Each tray comprises two similar portions 9, 9 hinged together at 10, and each portion is preferably square in plan and capable of completely covering a can 5 of the lower tier and supporting a can 6 of the upper tier. In a multiple row cabinet, like that shown in Figs. 1 and 2, the trays may be arranged 45 crosswise of the cabinet. In a single row cabinet they would necessarily extend longitudinally and of course even in a multiple row cabinet they may be arranged longitudinally, with adjacent trays set side by side across the width of the cabinet, but I prefer the arrangement shown. The hinge 10 is constructed to permit either portion 9 to be raised to or slightly beyond the vertical, as shown in Fig. 5 and in the case of the third tray from the left in Figs. 1 and 2. The 50 trays support the cans of the upper tier, one can 6 on each tray, and the trays are themselves supported by or over the cans 5 of the lower tier. It is simpler and more economical of vertical space to rest the trays directly on the cans 5 and this arrangement is to be preferred in some cases. It is of particular utility in the case of certain rebuilt cabinets, of which there are now large numbers in use, in which a repositioning of the refrigerating elements has reduced the vertical 55 space to just slightly more than enough to accommodate two superposed two-and-one-half-gallon cans. Interposition of the slight thickness of a tray 8 does not elevate the top of an upper can 6 too high to fit within such a cabinet, and this 60 economy of vertical space is therefore a very

valuable and important feature of the present invention. In other cabinets, where vertical space limitation is not a factor, the trays may be supported on means other than the lower cans, as by brackets or the like extending from the bottom 5 or side walls of the cabinet, and this expedient may be adopted where it is desired to replace one or more of the lower cans by an open lower zone space capable of accommodating packages of brick ice cream, boxes of ice cream bars, or 10 allied loose goods.

In using the invention, it is evident that access to any can of the upper tier may be had by simply removing the appropriate lid 3. Any can of the lower tier which happens to be beneath an unoccupied portion 9 of a tray 8 may be reached by raising that portion 9. To reach a can of the lower tier which is covered by a portion 9 which happens to be occupied by a can 6, the can 6 is slid over on to the companion portion 9 and the then unoccupied portion 9 is raised to expose the desired lower can 5. To facilitate this latter operation certain features are desirably incorporated in the trays as follows:

(1) The hinge 10 is disposed so as not to project upwardly above the surface on which the can rests. In this way no obstruction is offered to the free and easy sliding movement of the can from one portion 9 to the other.

(2) Skid rails or tracks may be formed on the can-engaging surfaces of the portions 9 to minimize the areas of the can and tray surfaces in contact and reduce the sticking consequent upon the freezing of condensation on these surfaces. In Figs. 4 and 6 I show suggested forms of such rails or tracks, designated 11 and 12 respectively, the construction of which is thought to be obvious.

(3) Upstanding side and end flanges 13 are preferably formed about the perimeter of each tray to stiffen the portions 9, maintain the can wholly on the tray, and prevent adjacent trays from interfering with each other when a portion 9 of one of them is being raised or lowered.

(4) Finger holds, like the corner pieces shown at 14, are preferably provided near the free ends of the portions 9 to render it easy for an operator to lift a portion which does not support a can but which covers a lower can to which access is desired.

(5) It is desirable to provide some sort of means to limit the angle through which the lifted portion may be moved, so as to prevent its collapsing on the companion portion when it is raised and there is no can supported on the tray. Of course, when a can is on the tray, the raised portion will rest against that can. Such a means is shown in Figs. 3 and 5, where the side flanges 13 are bevelled at their inner ends. These ends may abut each other to limit the angle of the raised portion, or they may be formed in parallel, adjacent planes, so as to clear each other and abut the floor of the companion portion of the tray.

(6) The portions 9 are preferably imperforate 65 and their edges extend beyond the peripheries of the lower cans. In this way the lower cans, which are preferably without lids, are protected from contamination by dirt, frost and the like which might otherwise drop into them. Any such foreign matter which finds its way into the cabinet will be caught by the trays and either be retained thereon or be shed therefrom at the hinge 10 or the ends thereof when a portion 9 is raised. It is evident that matter dropped from these 70

points cannot enter the cans 5 but will fall between them.

I come now to an explanation of the refrigerating and temperature advantages referred to hereinabove. In actual practice adjacent trays 8 are in edge abutting relation or substantially so, and the side and end walls of the cabinet are engaged or substantially engaged by certain edges of the trays adjacent thereto, although in Figs. 1 and 2 I have, in order to clarify the disclosure, exaggerated the spacings. That is to say, in actual practice all of the trays together, when the portions 9 thereof are all in horizontal position, which is their normal condition, extend substantially continuously from end wall to end wall and from side wall to side wall of the cabinet and constitute a partition separating the upper zone of the cabinet from the lower. This provides an effective and valuable barrier to inter-zone heat transfer by convection currents of air and results in a distinct improvement in temperature conditions within the cabinet, as will be evident from the following considerations:

Ice cream begins to melt at about 18° above zero Fahrenheit. The best keeping temperature for ice cream is generally considered to be about 5° above zero. The upper zone of a cabinet is always warmer than the lower, both because of the natural tendency of warm air within the cabinet to rise and because of the proximity of the upper zone to the top openings 2 through which warm air from the outside enters whenever a lid is removed. To compensate for this tendency toward unequal temperatures in the upper and lower zones, cabinets are generally provided with a greater length of coil in the upper zone than in the lower, as is shown in Fig. 2. In other words, more refrigerating effort must be expended in the top of the cabinet than in the bottom. Notwithstanding such coil disposition, a considerable temperature differential persists in cabinets unprovided with the new tray means. For example, tests of such cabinets have shown mean temperatures of 10° in the upper cans and 6° in the lower cans, or an average of 8°, these readings being taken sufficiently long after replacing all the lids to give a true indication of what may be regarded as permanent conditions. This temperature of the ice cream in the upper cans is too high for best preservation of the cream, but if it were reduced to the optimum point the cream in the lower cans would suffer from too low temperatures.

Similar tests of the cream in cabinets provided with the new tray means have shown upper can temperatures averaging 6° and lower temperatures of 4°, or a mean of 5°, which is the optimum. Neither of these extremes is appreciably above or below the optimum, so that all the cream is kept at practically ideal temperature conditions. The explanation of this result is probably that the partition formed by the several trays substantially isolates the upper zone from the lower, protecting the lower zone from warm air currents introduced when a lid is removed. The greater coil length present in the upper zone rapidly cools the warm air so admitted to the upper zone and confined thereto, and the isolated lower zone is never appreciably warmed by such air. Moreover, in many cases a lid is removed to give access to an upper can, and no portion 9 is raised, and in such cases the quantity of outer air which can be admitted is materially limited by the fact that the effective volume of cabinet space opened to the outer air is

substantially halved by the partition. The entire cabinet interior is not opened to swirling currents of outer air, as would be the case if no partition were present.

The trays are preferably made of sheet metal 5 of appropriate gauge and rigidity.

It will be appreciated that certain of the characteristics and features of the constructions herein explained, although desirable in themselves, may be dispensed with at the option of the designer without sacrificing other advantages of the essential invention. Various modifications may be introduced. The essential features of patentable novelty are defined by the appended claims, and all modified embodiments are to be 10 considered within the scope and purview of the claims to the extent that they incorporate the broad principles of the invention set forth in the claims, which are to be construed as limited only 15 by their express limitations and as required by 20 the state of the prior art.

I claim:

1. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, and a receptacle-supporting tray horizontally supported over two adjacent 25 receptacles of the lower tier, said tray comprising two portions, each having an area sufficient to accommodate a receptacle of the upper tier, hinged together whereby one portion may be raised to expose a receptacle of the lower tier 30 while the other portion remains horizontally supported over an adjacent receptacle of the lower tier.

2. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, and a receptacle-supporting tray resting 40 on two adjacent receptacles of the lower tier and supporting a receptacle of the upper tier, said tray comprising two portions, each having an area sufficient to accommodate a receptacle 45 of the upper tier, hinged together whereby one portion may be raised to expose a receptacle of the lower tier while the other portion rests on an adjacent receptacle of the lower tier.

3. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, a receptacle-supporting tray horizontally supported over two adjacent receptacles of the lower tier, said tray comprising two portions, each having an area sufficient to cover a receptacle of the lower tier and support a receptacle of the upper tier, hinged together whereby one portion may be raised to expose a receptacle of the lower tier while the other portion remains horizontally supported over an adjacent receptacle of the lower tier, and means associated with each portion adapted to be engaged by the fingers of 60 an operator when raising said portion.

4. A cold storage cabinet for ice cream and the like comprising an insulated box having an open top and closed sides and bottom adapted to contain superposed horizontal tiers of receptacles, 75

closure means for the top of the cabinet, cooling means in heat exchange relation with the cabinet interior, a receptacle-supporting tray horizontally supported over two adjacent receptacles of the lower tier, said tray comprising two portions, each having an area sufficient to cover a receptacle of the lower tier and support a receptacle of the upper tier, hinged together whereby one portion may be raised to expose a receptacle of the lower tier while the other portion remains horizontally supported over an adjacent receptacle of the lower tier, and ribs projecting above the upper surface of each of said portions for spacing the bottom of a receptacle of the upper tier above said surface.

5. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, a receptacle-supporting tray resting on two adjacent receptacles of the lower tier and supporting a receptacle of the upper tier, said tray comprising two portions, each having an area sufficient to accommodate a receptacle of the upper tier, hinged together whereby one portion may be raised to expose a receptacle of the lower tier while the other portion rests on an adjacent receptacle of the lower tier, and ribs projecting below the lower surface of each of said portions for spacing said surface above the top of a receptacle of the lower tier.

6. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, a receptacle-supporting tray resting on two adjacent receptacles of the lower tier and supporting a receptacle of the upper tier, said tray comprising two portions, each having an area sufficient to accommodate a receptacle of the upper tier, hinged together whereby one portion may be raised to expose a receptacle of the lower tier while the other portion rests on an adjacent receptacle of the lower tier, ribs projecting below the lower surface of each of said portions for spacing said surface above the top of a receptacle of the lower tier, and ribs projecting above the upper surface of each of said portions for spacing the bottom of a receptacle of the upper tier above said surface.

7. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, and a receptacle-supporting tray horizontally supported over two adjacent receptacles of the lower tier, said tray comprising two portions, each having an area sufficient to accommodate a receptacle of the upper tier, hinged together whereby one portion may be raised to expose a receptacle of the lower tier while the other portion remains horizontally supported over an adjacent receptacle of the lower tier, in combination with means carried by each portion to limit raising of said portion.

8. A cold storage cabinet for ice cream and the like comprising an insulated box having an open top and closed sides and bottom adapted to contain superposed horizontal tiers of receptacles,

closure means for the top of the cabinet, cooling means in heat exchange relation with the cabinet interior, and a receptacle-supporting tray horizontally supported over two adjacent receptacles of the lower tier, said tray comprising two portions, each having an area sufficient to accommodate a receptacle of the upper tier, hinged together whereby one portion may be raised to expose a receptacle of the lower tier while the other portion remains horizontally supported over an adjacent receptacle of the lower tier, each portion having a shoulder adapted to abut the other portion to limit raising of the shouldered portion.

9. A cold storage cabinet for ice cream and the like comprising an insulated box having an open top and closed sides and bottom adapted to contain two sets of receptacles arranged side by side, each set comprising an upper tier and a lower tier, closure means for the top of the cabinet, cooling means in heat exchange relation with the cabinet interior, and a receptacle-supporting tray extending transversely of the cabinet and horizontally supported over adjacent lower tier receptacles of the two sets, said tray comprising two portions, each having an area sufficient to accommodate a receptacle of the upper tier, hinged together whereby one portion may be raised to expose a receptacle of the lower tier while the other portion remains horizontally supported over the adjacent receptacle of the lower tier.

10. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, and a plurality of receptacle-supporting trays horizontally supported in the cabinet, each tray overlying two adjacent receptacles of the lower tier and supporting a receptacle of the upper tier and comprising two substantially imperforate portions hinged together whereby one portion may be raised to expose a receptacle of the lower tier while the other portion remains horizontally supported over an adjacent receptacle of the lower tier, and all of said trays together, when the portions thereof are all in horizontal position, extending substantially continuously from end wall to end wall and from side wall to side wall of the cabinet and constituting a partition separating the upper zone of the cabinet from the lower and substantially preventing inter-zone heat transfer by convection.

11. A cold storage cabinet for ice cream and the like comprising an insulated box having an open top and closed sides and bottom adapted to contain a tier of receptacles in the lower zone of the cabinet and a superposed tier of receptacles in the upper zone, closure means for the top of the cabinet, cooling means in heat exchange relation with the lower zone of the cabinet and cooling means of relatively greater capacity in heat exchange relation with the upper zone, and a plurality of receptacle-supporting trays horizontally supported in the cabinet, each tray overlying two adjacent receptacles in the lower zone and supporting a receptacle in the upper zone and comprising two substantially imperforate portions hinged together whereby one portion may be raised to expose a receptacle in the lower zone while the other portion remains horizontally supported over an adjacent

- receptacle in the lower zone, and all of said trays together, when the portions thereof are all in horizontal position, extending substantially continuously from end wall to end wall and from side wall to side wall of the cabinet and constituting a partition separating the upper zone of the cabinet from the lower and substantially preventing inter-zone heat transfer by convection.
- 10 12. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, and a receptacle-supporting tray horizontally supported over two adjacent receptacles of the lower tier, said tray comprising two portions, each having an area sufficient to accommodate a receptacle of the upper tier and substantially to cover one of said two receptacles of the lower tier, hinged together whereby one portion may be raised to expose one of said two receptacles while the other portion remains horizontally supported over the other, in combina-

tion with a flange upstanding from the free edges of said portions adapted to prevent foreign matter on the portions from dropping into the receptacles of the lower tier.

13. A cold storage cabinet for ice cream and the like comprising an insulated box having an open top and closed sides and bottom adapted to contain superposed horizontal tiers of receptacles, closure means for the top of the cabinet, cooling means in heat exchange relation with the cabinet interior, and a receptacle-supporting tray horizontally supported over two adjacent receptacles of the lower tier, said tray comprising two portions, each having an imperforate area sufficient to accommodate a receptacle of the upper tier and substantially to cover one of said two receptacles of the lower tier, hinged together whereby one portion may be raised to expose one of said two receptacles while the other portion remains horizontally supported over the other, in combination with a flange upstanding from the free edges of said portions adapted to prevent foreign matter on the portions from dropping into the receptacles of the lower tier.

WILLIAM P. CRISMAN. 25
